UNITED STATES PATENT OFFICE

WILLIAM G. BURHANS, OF KINGSTON, NEW YORK

LUBRICATING OIL CLARIFIER

Application filed November 20, 1931. Serial No. 576,408.

This invention relates to an improved lubricating oil clarifying device designed for installation in the oil circulating system of motors, particularly of the internal combustion engine type employed in present day automobiles.

The invention has reference to a novel oil filter which is an improvement on the type of filter illustrated in a patent granted to me under date of June 14, 1927, and identified as 1,632,461.

The present invention is characterized by a number of structural refinements and revisions providing a structure wherein a bodily removable and insertible filtering cartridge is the principal feature of distinction.

The specific structural details, relative arrangement and association, and commercial features and advantages will become more readily apparent from the following description and drawings.

In the drawings:

Figure 1 is a side elevational view showing the complete oil clarifier as constructed in accordance with the present invention.

Figure 2 is a top plan view of Figure 1.

Figure 3 is a central vertical sectional view with parts in elevation.

Figure 4 is a longitudinal vertical sectional view through the improved bodily removable cartridge.

Figure 5 is a bottom plan view of said cartridge.

Figure 6 is a fragmentary elevational view of a clamping cross-head.

Figure 7 is a plan view of a supporting ring disposed on the interior of the casing.

Figure 8 is a fragmentary plan view of a follower cup.

Figure 9 is a horizontal section on the line 9—9 of Figure 3.

In the drawings, it will be seen that the container or casing is generally designated by the numeral 10 and comprises a shell hav-

ing a cylindrical open top body portion 11 reduced in diameter as indicated at 12 to form an annular shoulder. The bottom portion of the casing is of semi-bulbous configuration as indicated at 13 to form a sediment 50 and water collecting trap and this is provided with an internally screw-threaded nipple 14 into which the drain cock 15 is tapped.

The numerals 16 designate a suitable attaching bracket for securing the device to a relatively stationary support 17 as shown in Figure 2.

As seen in Figure 3, the oil inlet is denoted by the numeral 18 and this is provided with a cut-off valve 19 of appropriate construction. The oil outlet at the top is distinguished by the numeral 20. The numerals 21 and 22 designate suitable couplings for the circulating pipe sections 23, 24, 65 and 25, it being understood that the oil enters the clarifier through the connection 18, passes upwardly and leaves through the connection 20 where it is returned by the piping to the crank case. 70

The internal filtering cartridge is distinguished as a unit by the numeral 26, and this is of composite construction. As seen in Figure 4, it comprises a fabric or gauze bag 27 having a burlap bottom 28. The bag 75 is open at its top and the mouth portion thereof embraces a felt closing disc 29. This novel container is filled with an appropriate filter 30 which is preferably a mixture of cotton and wool waste material. 80

The complete cartridge is removably inserted in the cylindrical body portion 11 and seated on a supporting ring 31 which is in turn seated on the shoulder or ledge 12. 85

A novel fluid-tight closure is provided for the upper end of the receptacle and this comprises an imperforate cupped cap 31 having a suitable rim 32 provided with a packing ring 33 clamped down on the upper end of the cylindrical body 11. This cap is pro- 90

vided in its crown portion with a depression 34 forming a seat for the adjacent end of the clamping screw 35. This clamping screw passes loosely through a hole in the 5 crown portion of a yoke 36 rigidly secured to the cap, and the upper end of the screw is fashioned with a finger-grip 37.

Attached to the indentation 34 is a semi-spherical apertured follower cup 38 which 10 conforms to and fits snugly down against the rounded end portion of the cartridge 26, as seen for example in Figure 3. This serves to compress the filler of the cartridge to insure effective results.

15 I now call attention to a cross bar or cross head 39 having its end portion 40 shaped to co-operate with hooks 41 on the upper ends of diametrically opposite arms 42 secured to the casing. The central portion 43 of the 20 bar 39 is threaded and the clamping screw is threaded therethrough and rests in the seat 34. Thus by turning the screw down the bar 39 backs up in the keeper hooks 41 and presses the cover firmly down against 25 the casing. This also forces the follower plate or cup 38 tightly down against the cartridge 26.

For installation in general, simply connect the pressure line with a side inlet 18 of 30 the clarifier and return from top connection 20 to the crank case. Under no circumstances, on any system, should the return from the clarifier be connected to pressure line or to bearings. It has been found also 35 that in order to realize the utmost value of this clarifier and when installation is made on dirty oiled motors, the cartridge should be changed frequently, perhaps every two or three hundred miles until the system is 40 thoroughly cleaned and the oil is clear.

Thereafter, the cartridge may be renewed when oil becomes unnecessarily dark or cloudy. The method of attachment and installation varies according to the particular 45 type of oil circulating system in which the clarifier is embodied as is obvious.

It is evident that the sediment and water will collect in the trap 13 from which it may be periodically drained by way of the 50 drain cock 15. It is further evident that the oil enters the clarifier at the lower side inlet and circulates around the sediment cap, the oil being forced up through the special cartridge and returned to the crank case 55 from the side top outlet 20.

The following points are a few of the commercial advantages is observed from actual usage and tests.

1. Save from fifty to seventy-five per cent 60 on oil consumption.
2. Eliminates valve and carbon jobs by at least seventy-five per cent.
3. Eliminates sticky valves.
4. Eliminates water dilution of oil in 65 crankcase.

5. Removes all discoloration from oil.

6. The only filter which permits the changing of the cartridge without the use of tools, said change being made in two minutes. 70

7. By far the least expensive cartridge renewal.

8. Doubles the life of the motor, when operating instructions are followed closely. 75

It is thought from the foregoing description that the advantages and novel features of the invention will be readily apparent.

It is to be understood that changes may be made in the construction and in the combination and arrangement of the several 80 parts provided that such changes fall within the scope of the appended claims.

I claim:

1. As a new article of manufacture, a cartridge for use in an oil clarifier of the 85 class described comprising a foraminous sack including a cup-like burlap base portion, a cloth body portion open at its top, a filler of waste, and a disc-like insert of felt overlying the upper end portion of the waste 90 and constituting a closure for the mouth portion of the sack.

2. As a new article of manufacture, a cartridge for use in association with an oil clarifier of the class described comprising a 95 sack of closely woven fabric having a bottom portion of coarse woven fabric, and a filler in said sack composed of cotton waste.

3. An oil clarifier of the class described 100 comprising a casing of cylindrical form open at its top and having a substantially semi-spherical lower end, the upper part of which is of less diameter than the major portion of the cylinder whereby a shoulder is formed at the juncture of said lower part with the 105 major part, a ring-shaped plate seated on the shoulder having a small centrally arranged opening, a cartridge located in the casing and seated on the ring-shaped plate, with the central part of its lower end covering 110 the opening in the ring-shaped plate, said cartridge having a rounded upper end, a cap for closing the upper end of the casing and having a dome-shaped part formed with a central depression, a perforated dome 115 shaped follower plate having its central part connected to the lower face of the depression part of the cap and engaging the upper end of the cartridge, a yoke having its extremities connected with exterior parts of the 120 cap, a cross bar passing between the yoke and the cap and having a threaded hole therein, a screw passing loosely through the bight of the yoke and thru the threaded hole in the cross bar with its lower end entering the depression in the cap, upstanding members connected to opposite sides of the top part of the casing and having hook-shaped upper ends for receiving the ends of 125 the cross bar, inlet means connected with 130

the lower part of the cylinder below the ring-shaped plate and outlet means connected with the top part of the cylinder.

4. As a new article of manufacture, a filtering cartridge comprising a sack formed of foraminous material, a bottom forming portion for the sack composed of material of coarser mesh than that of the sack, the top of the sack being open, a filler of filtering material in said sack and a closure for the top of the sack formed of fabric.

In testimony whereof I affix my signature.
WILLIAM G. BURHANS.
